FOREIGN PATENT DOCUMENTS

CH 137317 6/2011

* cited by examiner

Primary Examiner — Selina Sikder(74) *Attorney, Agent, or Firm* — The Webb Law Firm(57) **CLAIM**

The ornamental design for a push button, as shown and described.

DESCRIPTION

FIG. 1 is a perspective view of the claimed push button design;

FIG. 2 is a top view of the push button shown in FIG. 1; and,

FIG. 3 is a front view of the push button shown in FIG. 1. The broken lines shown in FIG. 3 depict portions of the push button that form no part of the claimed design.
